UNITED STATES PATENT OFFICE

FRANK B. ALLEN, OF LOWER MERION TOWNSHIP, MONTGOMERY COUNTY, PENNSYLVANIA, ASSIGNOR, BY MESNE ASSIGNMENTS, TO THE ALLEN-SHERMAN-HOFF COMPANY, OF PHILADELPHIA, PENNSYLVANIA, A CORPORATION OF PENNSYLVANIA

FURNACE CONSTRUCTION

Application filed November 18, 1924. Serial No. 749,807.

This invention relates to the construction of furnace bottoms and particularly bottoms for furnaces of the "burner" type in which combustible material is fed into the combustion chamber through burners.

It also relates to furnace construction in which means are provided for cooling the bottom walls and certain of the supporting structures thereof, and for leading the cooling fluid into the combustion chamber of the furnace.

It further relates to new and improved bottoms for furnaces of the burner type which are provided with means for simultaneously maintaining the temperature of the bottom below a predetermined maximum temperature, and preheating gases preliminary to their delivery into the combustion chamber of the furnace.

20 In furnaces of the burner type, i. e., furnaces in which the combustible material, such as oil, gas or pulverized fuel, is introduced into the combustion chamber through burners, as contrasted with stoker furnaces where 25 the combustible material is fed into the combustion chamber on a grate, the amount of solid material resulting from the combustion is somewhat more finely divided or present in smaller amounts than in the stoker type of 30 furnace and affords less protection to the bottom walls of the furnace against the heat of the flame. Furthermore when powdered coal is being burned not only does a comparatively small amount of ash accumulate in the furnace to protect the walls but a considerable 35 quantity of hot slag may form and collect directly on the furnace walls. The bottom walls of furnaces, or furnace bottoms of the burner type are thus often subjected to extreme 40 temperatures and severe service conditions tending to shorten their period of usefulness. Accordingly it may often be desirable or necessary to maintain the temperature of such walls and even of the metal structure supporting the same below a certain 45 maximum temperature.

My invention aims to provide a furnace bottom with efficient means for controlling the maximum temperature thereof which 50 means, however, is relatively inexpensive,

easy to construct and not readily susceptible to breakage or other factors tending to destroy its usefulness while in service.

In the drawings accompanying this specification and forming a part thereof—

55 Fig. 1 is a top plan view of a furnace bottom of a furnace embodying my invention.

Fig. 2 is a longitudinal view, partly in elevation and partly in section, taken on line 2—2 of Fig. 1.

60 Fig. 3 is a fragmentary, transverse, sectional view taken substantially on line 3—3 of Fig. 1.

65 Fig. 4 is an enlarged fragmentary detail view in section of my improved furnace bottom construction.

70 Figs. 5 and 6 are, respectively, plan and sectional views of a metal wall plate employed in my improved furnace bottom construction.

75 Fig. 7 is a fragmentary view of furnace bottom construction embodying my invention for cooling the walls and introducing gases heated by the walls into the combustion chamber of the furnace, and

Fig. 8 is a fragmentary view of furnace bottom construction embodying my invention and in which means are provided for conducting heated gases to the burner of the furnace.

80 Figure 9 is a top plan view, partly in section, similar to Fig. 1 but taken below the lining material 13 and through the passages 16, 12, 19 and 19a.

85 Figure 10 is a fragmentary vertical section taken substantially on line 10—10 of Fig. 9.

90 My invention contemplates the construction of a furnace bottom and supporting structures therefor which will be substantially self cooling. To this end I provide passages in the bottom walls through which cooling fluids may flow. I prefer that these passages should have inlet and outlet openings near the lower and upper ends of the furnace bottom and should extend upwardly 95 to permit the cooling fluid as heated to expand and rise therein, thus creating a current drawing in additional cooling fluid at a rate depending on the temperature of the wall and operating substantially automati-

cally. My invention also includes passages extending horizontally in the bottom and preferably communicating with the upper ends of the upright passages and so constructed, arranged and connected to associated parts as to insure flow of cooling fluids thereto.

One form of construction embodying my invention is shown in the accompanying drawings in which numeral 1 designates girders which support the furnace side refractory walls 2 and from which is supported and suspended a furnace bottom including a metal frame comprising inclined angle irons 3 and bottom members or castings 4, 4^a and 4^b, the latter being provided with the usual opening 5 through which material may be discharged from the furnace and with doors 6 to act as closures for the openings. The angle irons 3 carry on their inner surfaces detachable metal plates 7 which together constitute the outer metal shell of the furnace. These plates are each provided with outer peripheral strengthening flanges 8 and bolt securing lugs 9 and on the inner surface have spaced parallel ribs 10 which are arranged to extend substantially parallel to the angle irons 3. The ribs 10 are located similarly on each plate. The plates 30 constituting any given upright row thus have the ribs 10 extending vertically and in substantially upright alignment with each other. The plates 7 with their flanges 8 and lugs 9 are substantially the same as are shown and described in some detail in Patent No. 1,496,402, issued to me on June 3, 1924, except that ribs 10 are additional thereto. Slabs 11 composed of refractory material and of a size sufficient to bridge two or more of the ribs 10 engage the ribs and thus convert the spaces between the ribs into upwardly extending passages 12 through which cooling fluid may flow. Refractory lining material, preferably in brick form 13, is supported on the inner surface of slabs 11. In some instances one layer of bricks 13 may be sufficient but I have shown two such layers. The slabs and bricks comprise the liner portion of the furnace wall.

50 The slabs 11 and bricks 13 are supported primarily by the angle irons 3 and the members 4, 4^a and 4^b and are maintained in the position shown by suitable anchoring means, such for example as the upstanding flanges 14 on member 4^b. When the walls are substantially vertical additional means may be employed to prevent buckling and falling of the liner.

60 It will be noted that the plates 7 extend near to the top and on the inner side of the girders 1. Communicating with the passages 12 and extending across the top of the girders 1, I provide passages 16 for cooling fluid flowing upwardly through the passages 12. The passages are formed by interpos-

ing ribs composed of rolled steel sections between the top of girder 1 and the bottom of wall 2, as clearly shown in Fig. 4. The space between these ribs form passages serving as continuations of passages 12. In certain instances, where it is desirable to conduct gases into the combustion chamber 15 of the furnace at various places, I may form passages 17 in the upright walls 2 communicating with the passages 12 or with the extensions 16 thereof, as is more clearly shown in Fig. 7, apertures 17^a being formed in the wall 2 from the passages 17 to connect the latter with the interior of the combustion chamber or furnace 15. Also in certain instances it may be desirable to conduct the cooling fluid passing upwardly through passages 12 directly to the burner of the furnace. As shown in Fig. 8, this may be effected by providing a pipe or tube 18 in the form of a manifold to receive the fluids from several passages 12 and 16 and conduct the same into the combustion chamber through a burner (not shown).

It will be understood that I prefer to provide passages 12 or their equivalents in the lower part of the furnace bottom and extending upwardly over the girders 1. Where a furnace is provided with two or more bottom openings 5, I may also provide horizontal passages 19 for cooling the wall or walls between the said openings the outer ends of these passages 19 communicating with certain of the upright passages 12 as indicated in dotted lines at 19^a and Figs. 2, 3, 7 and 8, and more clearly in Figs. 9 and 10 whereby a draft through the passages 19 may be created automatically. It will be understood that when the furnace is in operation cooling fluid will of its own volition flow upwardly through the passages 12 as it becomes heated. thereby creating a continuous flow of cooling fluid in such passages and inducing a flow of fluid in the horizontal passages 19 and 19^a, which fluid would otherwise tend to remain more or less motionless unless movement thereof were artificially produced. The upward flow of cooling fluid in passages 12 is further expedited and facilitated, where gas or air constitutes the cooling fluid and where the passages 12 open into or are connected to the interior of the furnace 13, by the slight vacuum under which most furnaces operate and by the draft through the furnaces. Obviously, other means also could be employed to create a draft through these passages and therefore they need not be connected with passages. As shown these passages are formed between castings 4 and slabs 11 which rest on upright flanges 20 on castings 4. Apertures 20^a and 22^b in members 4 afford inlets for cooling fluids to the passages.

The lower ends of plates 7 are suitably cut away or perforated as at 21 to permit the ingress of suitable cooling fluid, preferably

air. If desired such fluid may be forced into the passages through these perforations by any suitable means, as will be readily understood by those skilled in the art.

8. Inlet openings 22, additional to openings 21 may be provided at the upper ends of passages 12 by leaving a space between the upper end of plates 7 and the top of girder 1 (see Fig. 4). Heated gas may be withdrawn or additional cooling gas introduced through openings 22.

In constructing a furnace embodying my invention the cast iron plates 7 can be readily shaped to conform to the needs of the 15 particular furnace. For example in building a corner of the furnace bottom the plates 7 may have their edges or corners sawed off to fit the corner and each other. The slabs 11 which are flat, relatively thin, refractory 20 members can be easily and more or less accurately chipped off to conform to the size of the available space. The same applies to the inner wall bricks 13. Any inaccuracies in 25 breaking or fitting the refractory members together will, of course, be filled with the fire clay mixture used as mortar between the bricks and slabs.

Although my invention has been described hereinabove in some detail in connection 30 with one particular form of furnace construction it is to be understood that such details are given for purposes of illustration only and that accordingly various changes 35 in the details shown and described may be made without departing from the scope of my invention.

Having thus described my invention so that those skilled in the art may be enabled to practice same, what I desire to secure by 40 Letters Patent is defined in what is claimed.

What is claimed:

1. In a furnace of the class described, wall supporting members and a furnace bottom supported thereby, the said bottom comprising 45 an inner refractory lining, an outer metal shell spaced apart therefrom and having integral projections cooperating with said refractory lining to form cooling fluid passages between the lining and shell, the said passages extending upwardly past the inner sides and adjacent to the side wall supporting members.

2. A hopper comprising a shell, supporting means for the shell, metallic spacers carried 55 by the inner surface of the shell and a refractory lining supported by said spacers, the shell, spacers and lining defining fluid cooling passages.

3. A hopper comprising a metal shell, supporting means therefor, inwardly and upwardly extending ribs carried by the shell, and a refractory lining carried by said ribs.

4. A hopper suspended from beams, comprising a metallic frame carried by the beams, 60 a metallic sheathing carried by the frame and

forming therewith a shell for the hopper, inwardly and upwardly extending ribs within the sheathing and carried thereby, and a refractory lining carried by the ribs and spaced thereby from the sheathing.

5. A hopper suspended from beams, comprising a metallic frame work connected with the said beams and depending therefrom, a metallic gate frame constituting the lower end of said frame work and provided with an opening through which material may be discharged from the hopper, a metallic sheathing carried by the frame work, inwardly and upwardly extending ribs on the inner surface of said sheathing, and a refractory lining supported upon said ribs, the sheathing, ribs and lining forming upwardly extending cooling fluid passages between the lining and sheathing.

6. A hopper suspended from beams, comprising a metallic frame work connected with the said beams and depending therefrom, a metallic gate frame constituting the lower end of said frame work and provided with an opening through which material may be discharged from the hopper, a metallic sheathing carried by the frame work, inwardly and upwardly extending ribs on the inner surface of said sheathing, and a refractory lining supported upon said ribs in spaced relation to the sheathing forming upwardly extending cooling fluid passages extending in cooling relation to the tops of the beams.

7. A hopper wall comprising a supporting frame work, an outer shell carried thereby and an inner refractory lining carried by said shell upon inwardly extending ribs formed integral with said shell, the shell, lining and ribs defining upwardly extending cooling fluid passages.

8. A hopper wall comprising a supporting frame work, an outer shell carried thereby, a plurality of spaced normally upwardly extending ribs carried by the inner surface of said shell and a refractory lining supported by said ribs.

9. A hopper wall comprising a supporting frame work, an outer shell carried thereby, a plurality of substantially normal upwardly extending ribs carried by the inner surface of said shell and a refractory lining carried upon said ribs and forming with the ribs and shell upwardly extending cooling fluid passages.

10. A hopper wall comprising a frame work suspended from beams, a metal shell carried by said frame work and provided with upwardly extending normal ribs on its internal surface, a refractory lining supported upon said ribs and forming therewith and with the shell upwardly extending cooling fluid passages, outwardly extending cooling

fluid passages over the top of the beams, the passages in the hopper walls communicating with the passages over the beams.
